UNITED STATES PATENT OFFICE.

HORACE D. PARKE, OF SYRACUSE, NEW YORK.

COMBINED STEP-LADDER AND IRONING-BOARD.

SPECIFICATION forming part of Letters Patent No. 335,714, dated February 9, 1886.

Application filed November 15, 1884. Serial No. 148,057. (Model.)

To all whom it may concern.

Be it known that I, HORACE D. PARKE, a citizen of the United States, residing at Syracuse, in the county of Onondaga and State of New York, have invented certain new and useful Improvements in a Combined Step-Ladder and Ironing-Board; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 Figure 1 of the drawings is a representation of this invention, and shows a top view arranged to receive an ironing-board. Fig. 2 is a vertical section of the same with the board on top, the section being taken where the broken line $\alpha\alpha$ is marked on Fig. 1. Fig. 3 is a perspective view showing the device arranged as a ladder. Fig. 4 is a detail view to show the brace of the ladder. Figs. 5, 6, and 7 are detail views of the brace-locking devices.

25 This invention has relation to a device which is adapted to be convertible to an ironing-board, wash-bench, step-ladder, bosom-board, &c.; and it consists in the construction and novel arrangement of parts, as will be herein-30 after more fully set forth, and particularly pointed out in the claims.

Referring to the accompanying drawings by letter, a indicates the main frame, which constitutes the bed of the wash-bench and also the 35 intermediate section of the ladder; b , the leg-sections, which also constitutes the top and bottom sections of the ladder, respectively, and c is the brace-section for the entire ladder. The main frame a is pivoted at opposite ends 40 to the inner sides of the respective legs by means of a transverse rod, A , and is provided on its under side, about midway its length, with equidistant transverse rounds or braces d , carrying upwardly-extending hooks B , to 45 receive a spring fastening device at the inner or free ends of the brace-arms C , which are hinged at their opposite ends to the lower portion of the respective leg-sections. The fastening devices at the ends of the brace-arms 50 are peculiar in construction, being of a form substantially as shown at D D' , having a lateral longitudinal flange, e , to engage the said

arm, as shown, and a projection provided with an eye, f , to engage the hooks on the intermediate rounds, d , of the main frame a . These 55 fastening devices D D' are also provided on their opposite longitudinal sides with an oblique flange or projection, g , which is designed to spring under the outer ends of the said braces, respectively, when the whole is folded 60 up, which will prevent the said arms from falling down, and one of these castings, as D' , is provided at its outer end with an eye, h , to engage a stud, i , arranged upon a hinged brace-arm, n , of the ladder brace leg-section c , 65 whereby the same may be held fixed with relation to the ladder. The main frame a is also provided near its opposite ends with turn- 70 buttons l , which are designed to engage the leg-sections, as shown, and hold the same fixed with relation to said main frame in forming the ladder.

The leg-sections b are designed to extend vertically above the main section a to receive and support an ironing-board or the like. 75

The brace leg-section c is composed of an upper or inner section, E , which is pivoted within one end of the frame by a transverse rod, m , passing through the longitudinal rails of the said frame, and two long hinged legs, F , 80 which are kept apart by means of a flat or other suitable spring, G , and are braced laterally by a transverse arm, n , which is hinged at one end to the inner side of one of the legs F , and engaged at its opposite end through an 85 eye of the said arm by a loop or hook lug, p , secured on the inner side of the opposite leg, as shown. From the upper flat side of this brace-arm n , at one end thereof, is hinged a brace-arm, H , which in its normal position 90 extends longitudinally oblique with relation to the leg-section c , and is provided at its free end with an eye or perforation to engage a stud, I , arranged upon the inside of the opposite leg F . Thus it will be seen that when 95 the perforation at the outer end of the arm is brought to engage the stud I the arm n will be forcibly held down upon the hook-lug on the inner side of one of the legs F , when the entire section will be firmly and securely 100 braced. The oblique brace-arms H being hinged near the hinged end of the transverse arm n , when the former is disconnected from the stud on the inner side of one of the legs F and

the latter brace-arm raised from its free end the said brace will be carried upwardly and closely against the opposite leg F, where it slides beneath the head of a screw, as shown 5 at J, which will prevent its leaving such position until the arm n is again thrown down to brace the legs F; and as the stud on the arm n is designed to fit snugly an aperture within the brace H it will not fall or disconnect of 10 its own accord. The hooks on the intermediate transverse bars of the frame a are provided on one side with an under shoulder, r, and the eyes of the castings on the leg-section braces are provided with springs L, arranged 15 as shown, to insure a proper engagement of the eye with the said hook beneath its shoulder when the parts are brought together.

When it is found desirable to form a wash-bench, the braces of the leg-section c are folded 20 up and the legs F let in between the side rails of the main frame a and the leg-sections b b swung out in a vertical position and securely braced by means of the brace-arms C and C'. Then by simply placing a board upon 25 the upper ends of the leg-sections an ironing-table may be formed; and when it is desired to convert the device into a step-ladder the leg brace-arms C C' are first disconnected at their outer ends, and after the section c has 30 been swung out and braced, as described, the leg-sections b b are swung around on their pivots to form an extension of the frame a, where they are secured by the turn-buttons on the said frame, the rounds of the same 35 forming stops for the movement in one direction. One of the braces, C, is then hooked over the stud on the upper flat side of the brace n of the section c, when the ladder will be firmly braced in an inclined position.

40 One of the leg-sections b is provided at its upper end with a cross-bar, A', which is pivoted at opposite ends in the respective legs thereof, and is provided with a central vertical recess, a', adapted to engage a vertical circular stud, b', arranged on the under side of the ironing-board, whereby both a vertical and lateral hinge or pivotal joint may be formed 45 between the said board and leg-section. This board Z is also provided at one end on its upper side with two strips or cleats, which are arranged transversely at an interval for the reception of one of the edges of a bosom-board.

The whole device when not in use may be 50 folded up into a flat parcel of rectangular contour for convenient transportation.

Having thus described my invention, what I claim, and desire to secure by Letters Patent, is—

1. The combination, with the main frame constituting the intermediate section of the 60 ladder, of the pivoted leg-sections composing the upper and lower sections of the ladder, and means, substantially as described, for bracing the same, and the leg-section pivoted at one end to the main frame and adapted to 65 be thrown outward to brace the ladder, substantially as shown and described.

2. The combination, with the main frame a, of the pivoted legs b, the pivoted braces C C', having the apertured castings D D', respectively adapted to engage the hooks B on the rounds or bars of the said frame a, substantially as specified, the leg-section c, having a cross-bar, n, and the stud i, projecting from the cross-bar to engage an eye, h, extending 75 from the casting D', substantially as and for the purposes set forth.

3. The combination, with the main frame, of the leg-sections b, the section c, having the brace-arms H and n, arranged to operate substantially as specified, and the brace C', pivoted to one of the leg-sections and provided with a catch to engage the brace-section c, as and for the purposes set forth.

4. The combination, with the ladder-section, 85 of the brace-section c, consisting of the legs F, the arm n, hinged to the inner side of one of the legs F, and provided at its opposite end with an aperture to engage the lug on the opposite leg, and the oblique brace-arms H, 90 hinged to the said arm n and provided at its outer end with an aperture to engage a stud on the opposite leg F, all adapted to operate substantially as specified.

5. The main frame having the braces C C', 95 provided with the castings D D', having lateral flanges to engage the opposite ends of the said braces and hold the same folded, substantially as specified.

6. The combination, with the main frame 100 having its intermediate rounds provided with the hooks or lugs B, having a lateral shoulder, of the pivoted legs, and the braces pivotally connected at one end to the legs and at 105 their other ends with apertured castings D D', respectively, said castings having a spring, as L, located to one side of the aperture in each, to cause an automatic locking of the hooks and castings, substantially as shown and described.

In testimony whereof I affix my signature in 110 presence of two witnesses.

HORACE D. PARKE.
